SELECTIVE CONTROLLING AND INDICATING APPARATUS

Clarence S. Snavely, Pittsburgh, Pa., assignor to
The Union Switch & Signal Company, Swiss-
vale, Pa., a corporation of Pennsylvania

Continuation of application Serial No. 181,057,
April 5, 1927. This application November 7,
1931, Serial No. 573,593

45 Claims. (Cl. 246—3)

My invention relates to selective controlling and indicating apparatus of the type comprising means located at one point, such as a train despatcher's office, for selectively controlling traffic 5 governing apparatus located at remote points, and means for indicating the condition of such apparatus at the despatcher's office. Apparatus embodying my invention is particularly suitable for, though in no way limited to, the control and 10 indication of railway switches and signals in general, in a centralized traffic controlling system for railroads, but as herein illustrated is specifically arranged for the control of train order signals located at a remote station provided with a "middle order" siding.

The present case is a continuation of my pending application, Serial No. 181,057, filed April 5, 1927, for Selective controlling and indicating apparatus.

20 I will describe one form of controlling and indicating apparatus applied to a middle order signal system, and will then point out the novel features thereof in claims.

In the accompanying drawings, Fig. 1 is a diagrammatic view showing one form of controlling and indicating apparatus embodying my invention. Fig. 2 is a view showing in elevation a portion of the apparatus illustrated in Fig. 1 and also embodying my invention. Fig. 3 is a view 25 showing a portion of the apparatus illustrated in Fig. 2 with certain of the parts removed to show the construction. Fig. 4 is a side view of one of the clutches P of Figs. 1 and 2. Fig. 5 is a side view partially sectioned showing one of the code 30 keys K and the associated clutch P. Fig. 6 is a view showing a track switch controlled by the apparatus of my invention.

Similar reference characters refer to similar parts in each of the several views.

40 Referring first to Fig. 1, the reference character A designates a stretch of track provided with a middle order siding I. Two signals designated by the reference characters W and E, respectively, are located adjacent the siding I for controlling traffic over the main track. These signals 45 may be of any suitable form, and as here shown signal W controls westbound traffic while signal E controls eastbound traffic and each signal when clear gives an indication conflicting with the indication of the other signal when clear. The two signals W and E are selectively controlled from a remote point, such as a despatcher's office, over line wires 4 and 5. The despatcher's equipment 50 comprises a plurality of normally unwound code keys K¹, K² and K³. Code keys of the type de-

scribed are well known in the art and it is thought to be unnecessary to describe them in detail in this application. For present purposes it is sufficient to state that each code key K comprises a code wheel 7 operating a contact 8 in such manner that when the key is first wound and then released, the consequent movement of the code wheel periodically opens and closes the associated contact 8. Each of the code keys K, when operated, supplies a distinctive control code to the line wires 4 and 5. As shown in the drawings, a battery 18 has a positive terminal B¹ constantly connected with wire 5 and when the contact 8 of any one of the code keys K¹, K² or K³ is closed, wire 4 is connected with terminal C¹ of this battery. The operation of any one of the code keys K therefore supplies periodically interrupted current from battery 18 to the line wires 4 and 5 to supply a control code to these line wires, the characteristic of which code depends upon the disposition and arrangement of the projections 7a on the code wheel. It should be noted that when the keys K are at rest, all contacts 8 are open, and battery 18 is disconnected from wire 4.

Located adjacent the siding I I provide code receiving apparatus comprising a quick acting line relay N and a plurality of code responsive relays or selectors S¹, S² and S³, each comprising an operating winding 10 and a movable member 11 operated thereby. When selector S¹ is deenergized, the parts occupy the positions in which they are illustrated in the drawings. When the winding 10 is supplied with the code transmitted by code key K¹, the member 11 is moved into the position in which contact 13—11—12 is closed, but this contact is not closed by operation of keys K² or K³. In similar manner, selector S² is responsive only to the control code delivered by code key K² so that the normally closed contact 14 is open only when the key K² has been operated to actuate the selector S². Furthermore, selector S³ which has a code setting corresponding to the control code delivered by key K³ is arranged to close contact 13—11—12 when supplied with such code. The selector S³ is also provided with a second contact 15—16 which is normally open but is arranged to be closed when the selectors S¹, S² and S³ are receiving any of the codes delivered by the keys K¹, K² or K³. The operating mechanisms of the selectors may, for example, be similar to those disclosed in Patent No. 1,343,256, granted June 15, 1920 to J. C. Field, for Selectively operated circuit controlling devices, and the contacts of the selectors 55

may be arranged as shown in the drawing to produce the results described.

I will now describe the manner in which the selectors S¹, S² and S³ are supplied with energy in accordance with the control codes delivered to the line wires 4 and 5 by the keys K¹, K² and K³. The line relay N is provided with a circuit which passes from wire 5 through wire 157, winding of relay N, wire 158, back contact 24 of a relay f, wire 159, back contact 26 of relay f and wires 160, 128 and 129 to line wire 4. The control of relays f and j will be described in detail hereinafter, but it will be seen that when these two relays are deenergized, relay N is connected directly with line wires 4 and 5 so that relay N responds to the control code impulses delivered to the line wires by the code keys K located at the despatcher's office. Energy is supplied to the operating windings 10 of the selectors S¹, S² and S³ from any suitable source of energy such as a battery 25 the terminals of which are connected with line wire 4 and a line wire 6 respectively. The armatures 27 and 28 of relay N constitute a pole changer for reversing the polarity of the current supplied to the operating windings 10 of the selectors in accordance with the operation of relay N. When one of the keys K at the despatcher's office is operated to supply a control code to the line wires 4 and 5, relay N is energized by each impulse of such code, provided relays f and j are deenergized. Each time relay N is energized, and each time it is deenergized, it reverses the polarity of the current supplied to the operating windings 10 of the selectors S¹, S² and S³ and a surge of current is therefore delivered to each operating winding 10 for each operation of relay N. It will be plain, therefore, that the energy supplied to the operating windings 10 of the selectors is a faithful reproduction of the control codes supplied to the line wires 4 and 5 by the control keys K located at the despatcher's office. A condenser 17 is inserted in series with the winding 10 of each selector so that when relay N is at rest, no energy is consumed in the operating windings.

If code key K¹ is operated to actuate selector S¹, the contact 13-11-12 of this selector closes and completes a pick-up circuit for a stick relay F¹ over which the current flows from terminal B of a suitable source of energy, (adjacent relay f on the drawing) through wires 29 and 30, contact 13-11-12 of selector S¹, wires 31 and 32, winding of relay F¹, wire 33 and back contact 34 of relay F³ to terminal C of the same source. The contact of selector S¹ is closed only for a brief interval, but the relay F¹ is maintained in its energized condition by virtue of a stick circuit which may be traced from terminal B, through wire 29, contact 13-14 of selector S², wires 39 and 40, front contact 41 of relay F¹, wires 42 and 32, winding of relay F¹, wire 33 and back contact 34 of relay F³, to terminal C. It follows that relay F¹, having once been energized, remains in its energized condition as long as contact 13-14 of selector S² is closed and relay F³ is open. When relay F¹ becomes energized, the closing of its front contacts energizes the operating mechanism of signal E, the circuit for such mechanism passing from terminal B, through front contact 35 of relay F¹, wire 36, operating mechanism of signal E, wire 37, and front contact 38 of relay F¹ to terminal C. Signal E therefore moves to the proceed position. If the operator in the despatcher's office wishes to restore the signal E to the stop position, he operates the code key K². This operates selector S² to open its back contact 13-14, thereby interrupting

the stick circuit for relay F¹ and allowing that relay to become deenergized. This breaks the operating circuit for the signal E and allows the signal to return to the stop position. In similar manner, if the despatcher operates code key K³ to actuate selector S³, stick relay F³ becomes energized over its pick-up circuit which is similar to the pick-up circuit already traced for relay F¹. Relay F³ is subsequently maintained in its energized condition as long as the contact of selector S² remains closed, by virtue of a stick circuit including front contact 43 of relay F³ and contact 13-14 of selector S². When relay F³ becomes energized, signal W is moved to the proceed position, and when the operator subsequently wishes to return this signal to the stop position he may do so either by operating code key K² to actuate selector S² and break the stick circuit for relay F³ at contact 13-14, or by operating code key K¹ to actuate selector S¹ to pick up relay F¹ and thereby break the stick circuit for relay F³ at back contact 38. Relay F¹ may likewise be released by picking up relay F³ to open back contact 34. It is thus clear that a signal may be restored to stop either by transmission of a stop code or by clearing the opposing signal.

It is desirable to provide an indication, in the despatcher's office, of the condition of the apparatus controlled by the keys K¹, K² and K³. For this purpose there are provided, adjacent the middle order siding, a plurality of starting relays each designated by the reference character G with a suitable distinguishing exponent and each arranged when energized to effect the transmission of an indication code to the despatcher's office. Each starting relay G is a stick relay arranged to be picked up by a momentary impulse of current and to then remain energized to store the code until its transmission is effected. The starting relays G⁶ and G⁷ are controlled in accordance with the conditions of signals W and E respectively. This control is accomplished in part by two circuit controllers T^W and T^E operated by the signals W and E respectively, and in part by relays F³ and F¹. Each of circuit controllers T^W and T^E is normally open and comprises a contact 44-46 arranged to be closed momentarily, when the associated signal is moving to the proceed position, just before the signal reaches its full proceed position. Each of the circuit controllers T also comprises a contact 44-45 arranged to be closed momentarily just before the signal moves into its full stop position.

If signal E is moved to its proceed position by energization of relay F¹, contact 44-46 of circuit controller T^E will be closed momentarily just before the signal completes its stroke. As a result, current will flow from terminal B, through contact 44-46 of circuit controller T^E, wires 47 and 48, front contact 49 of relay F¹, wires 50 and 51, winding of relay G⁶, wire 52, and a contact 21 the operation of which will be described hereinafter, to terminal C. If contact 21 is closed, therefore, starting relay G⁶ will have its pick-up circuit momentarily closed just before signal E reaches its proceed position. As soon as relay G⁶ becomes energized, a stick circuit for this relay becomes closed, which circuit is from terminal B over front contact 53 of relay G⁶, through the winding of the relay, wire 52, and contact 21 to terminal C. Relay G⁶, having once been energized, is therefore maintained in its energized condition as long as the contact 21 is closed. The pick-up circuit for relay G⁶ is provided with a

branch which passes from terminal B, through contact 44-46 of circuit controller TW, wires 54 and 47, front contact 55 of relay F³, to wire 51. It follows that relay G⁶ is energized when either 5 of the signals W or E moves to its proceed position provided the associated relay F is energized; and that the relay G⁶ is then held closed until the associated contact 21 opens.

In similar manner when either of the signals W 10 or E is restored to the stop position, starting relay G⁷ becomes closed due to the momentary closing of contact 44-45 of circuit controller TW or T^E. When signal W returns to the stop position, the pick-up circuit for relay G⁷ passes from terminal 15 B, through contact 44-45 of circuit controller TW, wires 56 and 57, back contact 58 of relay F¹, wire 59, back contact 60 of relay F³, wire 61, winding of relay G⁷, wire 62 and an associated contact 21 to terminal C. When signal E is re- 20 turned to its stop position a pick-up circuit for relay G⁷ is closed from terminal B through contact 44-45 of circuit controller T^E and wires 63 to wire 57 and thence as before through relay G⁷ to terminal C. If, therefore, relays F¹ and F³ 25 are both deenergized, relay G⁷ will become energized if either of the signals W or E moves to the stop position. Relay G⁷, having once been energized, is thereafter kept energized as long as its associated contact 21 is closed, by virtue 30 of a stick circuit which passes from terminal B through front contact 64 of relay G⁷, wire 65, winding of relay G⁷, wire 62, contact 21 and back to terminal C.

It is desirable also to indicate in the despatcher's office the movements of trains past the signals W and E. For this purpose the track rails adjacent these signals are divided, by means of insulated joints 2, to form two track sections a-b and b-d, the junction of which is prefer- 35 ably located adjacent the signals W and E. Each section a-b and b-d is provided with a track circuit, and track circuit current is supplied to the rails of each of these sections by a battery 3 connected across the rails of the section. An 40 interlocking relay R is provided with two windings r¹ and r² connected across the rails of the two sections a-b and b-d, respectively, and serves as a direction relay to indicate which sec- 45 tion is first occupied, thus indicating the direc- 50 tion of movement of a train past signal W or E into the adjacent non-track-circuited stretch of track. The relay R comprises four front contacts 66, 67, 69 and 70, and two back contacts 68 and 71, and may be any of the well known forms 55 of interlocking relays customarily employed in railway signaling systems. One form of relay suitable for this purpose is disclosed in Letters Patent of the United States, No. 799,452, granted September 12, 1905, to W. W. Coleman. When 60 the sections a-b and b-d are both unoccupied, windings r¹ and r² are both energized so that all of the front contacts of relay R are all closed and the back contacts are open. If an eastbound train enters section a-b, front contacts 66 and 67 open and back contact 68 closes. Current 65 then flows from terminal B, through back contact 68 of relay R, wire 72, and the winding of a slow releasing relay k to terminal C. Relay k therefore becomes energized. As the eastbound 70 train enters section b-d, front contact 70 opens, but due to the interlocking characteristics of the relay, back contact 71 does not close and front contact 69 remains closed. When the train vacates section a-b, the front contacts 66 and 67 75 close and back contact 68 opens, but contact 69

remains closed and contact 71 remains open. Relay k therefore becomes deenergized, but due to its slow releasing characteristics an interval of time elapses during which the front contacts of this relay remain closed. During this interval, current flows from terminal B, through wires 73 and 74, front contact 69 of relay R, wire 75, front contact 67 of relay R, wire 76, front contact 77 of relay k, wire 78, winding of relay G⁴, wire 79, and the associated contact 21 to terminal C. Relay G⁴ therefore becomes energized, but as soon as relay k opens, this pick-up circuit for relay G⁴ is interrupted. Relay G⁴ is provided with a stick circuit which passes from terminal B, through front contact 88 of relay G⁴, wire 81, winding of 10 relay G⁴, wire 79, and contact 21 to terminal C, so that relay G⁴ remains in its energized condition as long as contact 21 remains closed. When the eastbound train vacates section b-d, winding r² becomes energized, thereby restoring the 15 relay R to its normal condition. It will be plain from the foregoing, that when an eastbound train passes signal E, relay G⁴ becomes energized and that this relay thereafter remains closed until contact 21 opens. In similar manner, if a west- 20 bound train enters section b-d, winding r² of relay R becomes deenergized, thereby closing back contact 71 and opening front contacts 69 and 70. The closing of back contact 71 connects terminal B with wire 72 and therefore energizes relay k. 25 When the train enters section a-b, front contact 67 opens, but due to the interlocking characteristics of the relay, front contact 66 remains closed and back contact 68 remains open. When the train vacates section b-d, front contacts 69 30 and 70 close and back contact 71 opens so that relay k becomes deenergized. In the brief 35 interval during which the front contacts of the relay k remain closed, however, due to its slow acting characteristics, an impulse of energy is delivered to relay G⁵ over a circuit which passes from terminal B, through wire 73, front contact 66 of relay R, wire 82, front contact 79 of relay R, wire 83, front contact 84 of relay k, wire 85, winding of relay G⁵, wire 86, and the associated 40 contact 21 back to terminal C. Relay G⁵ is subsequently maintained in its energized condition 45 as long as contact 21 remains closed, by virtue of a stick circuit including front contact 87 of relay G⁵. The relay R is restored to its normal condition 50 when the westbound train vacates section a-b.

The starting relays G⁴, G⁵, G⁶ and G⁷ control automatic indication code transmitting apparatus designated in general by the reference character Q and illustrated in detail in Figs. 2, 3, 4 and 5. Referring now to these views as well as to Fig. 1, the apparatus Q comprises a motor M which operates a shaft 88 provided with four worms 89, 90, 91 and 92 (Fig. 2). Each of these worms at times operates a code key designated by the reference character K with an appropriate distinguishing exponent, there being one key for each starting relay G. These keys are similar to the keys K¹, K² and K³ except that instead of being manually operated each key is arranged to be wound by the motor M, and is then released automatically to transmit an impulse combination, or code, to the line wires 4 and 5. The winding of the keys K⁴ to K⁷ is effected by means of 60 sending magnets, or electric clutch mechanisms, designated by the reference character P with a distinguishing exponent, which function as repeater relays for the relays G, there being one 65 sending magnet or clutch for each key. The 70 sending magnet or clutch for each key. The 75

clutches are interposed between the operating spindles 93 (Fig. 5) of the code keys K and the corresponding worms on the motor shaft 88. As best shown in Fig. 5, each clutch P comprises a magnetizable barrel 94 pinned to the spindle 93 of the associated code key K. This barrel is provided with an annular recess 95 which contains a winding 96. Associated with the barrel 94 is a magnetizable armature 97 rigidly attached to a worm wheel 98 meshing with one of the worms on the motor shaft 88. When winding 96 is de-energized the worm wheel 98 is disconnected from the barrel 94 of the clutch P so that if, under these conditions, the motor M is operated, the worm wheel turns without moving the barrel of the clutch. If, however, the motor is operated while winding 96 is energized, the barrel 94 is rotated with the armature 97 driven by the worm wheel and thereby serves to rotate the spindle 93 of the code key K. Attached to the barrel 94 is a contact operating lug 23 as best shown in Fig. 3. When the barrel occupies its normal position corresponding to the unwound position of the code key, as illustrated in Fig. 3, the lug 23 closes a contact 20 but this contact opens as soon as the barrel of the clutch is moved away from this initial position by the operation of the motor M when the clutch P is energized. The lug 23 on the clutch barrel 94 also operates two normally closed contacts 21 and 22 which are arranged to be opened when the barrel of the clutch moves into the position which corresponds to the fully wound condition of the associated code key K. Referring now again to Fig. 1, it is this contact 21 operated by each of the clutches which is included in the stick circuit for the associated starting relay, and each of the starting relays is therefore held closed after having once been energized until the associated key is fully wound.

In explaining the operation of the automatic indication code transmitting apparatus Q, I will first assume that one of the signals E or W is cleared so that relay G⁶ becomes energized as has been described hereinbefore. Relay G⁶ is held in its energized condition by its stick circuit including its own front contact and contact 21 operated by the clutch P⁶. The energization of relay G⁶ completes a circuit from terminal B, through back contact 99 of a relay h, wire 100, front contact 101 of relay G⁶, wires 102 and 103, contact 20 operated by clutch P⁷, wire 104, contact 20 operated by clutch P⁵, wire 105, contact 20 operated by clutch P⁴, wires 107 and 108, winding of a master relay j to terminal C. Master relay j therefore becomes energized and closes its front contacts. Current then flows from terminal B, through front contact 109 of relay j, wire 110, and the field and armature of motor M to terminal C. The motor M therefore operates to drive shaft 88 and to operate the worms 89, 90, 91 and 92. Furthermore, the energization of relay j completes a circuit from terminal B, through front contact 109 of relay j, wire 111, back contact 112 of relay G⁴, wire 113, back contact 114 of relay G⁵, wire 115, front contact 116 of relay G⁶, wire 117, and the energizing winding of the clutch P⁶ to terminal C. The clutch P⁶ is therefore energized to couple the key K⁶ with the motor M, and so that key K⁶ becomes wound up, but the circuits for the remaining clutches P⁴, P⁵ and P⁷ are all open so that none of the other code keys K⁴, K⁵ and K⁷ is coupled with motor shaft 88 to wind up such key. It should be noted that as soon as the winding operation of key K⁶ com-

mences, the resulting movement of lug 23 on the clutch barrel (Fig. 3) allows contact 20 to open, thereby interrupting the circuit previously traced for relay j. This relay is now maintained in its energized condition, however, by a stick circuit which passes from terminal B, through back contact 99 of relay h, wire 100, front contact 101 of relay G⁶, wire 102, contact 22 operated by clutch P⁷, wire 119, contact 22 operated by clutch P⁶, wire 120, contact 22 operated by clutch P⁵, wire 121, contact 22 operated by clutch P⁴, wire 122, front contact 123 of relay j, wires 124 and 108, and the winding of relay j to terminal C. It should be observed that this stick circuit includes contact 22 operated by clutch P⁶. As soon as the winding operation of code key K⁶ is completed, contacts 21 and 22 operated by the clutch P⁶ open. The opening of contact 22 interrupts the stick circuit for relay j, allowing this relay to become deenergized, thereby opening the circuit for the motor M at front contact 109. The opening of contact 109 also deenergizes the clutch P⁶ to release the code key K⁶ and allow the key to transmit an indication code as will be described hereinafter. Moreover, the opening of contact 21 on clutch P⁶ breaks the stick circuit for relay G⁶ and allows this relay to become deenergized. When the code key K⁶ is released after having been wound up, it operates to intermittently close contact 8 in accordance with a predetermined indication code. During this operation of the code key the contact 8 supplies an indication code to the line wires 4 and 5 from battery 19, the positive terminal B of which is constantly connected with line wire 5 and the negative terminal of which is connected through brush 9 bearing on the code wheel 7 of the key K⁶, contact 8, wires 125, 126, 127, 128 and 129 to line wire 4. The indication code thus supplied to the line wires 4 and 5 operates code receiving apparatus 40, comprising a quick-acting line relay L connected across these line wires in the despatcher's office, which relay controls the supply of current to the operating windings 10 of a plurality of selectors S⁶, S⁷, S⁴ and S⁵ in the same manner that relay N controls the supply of current to the operating windings of selectors S¹, S² and S³. The selectors in the despatcher's office are each arranged to be operated to close the associated contact 13-11-12 only when the indication code supplied to the selector is transmitted from the code key of apparatus Q having a corresponding exponent. The operation of the key K⁶ therefore actuates selector S⁶, but does not actuate the remaining selectors at the despatcher's office. When the selector S⁶ is operated, current flows from terminal B¹, through contact 13-11-12 of selector S⁶, wire 130 and winding 131 of relay J, to terminal C¹. Relay J, therefore becomes energized to close contact 132-132^a and current then flows from terminal B¹, through contact 132-132^a of relay J, wire 133, and lamp 134 to terminal C¹. The lamp 134 is a part of a visual indicator X comprising a plurality of such lamps selectively controlled to inform the operator in the despatcher's office of the condition of the apparatus at the middle order siding. When lamp 134 is lighted, it informs the operator that one of the signals is in the proceed position. The operation of the apparatus Q when one of the other indication relays G becomes energized will be readily understood from the foregoing. For example, if one of the signals W or E returns to the stop position, so that relay G⁷ becomes energized, the apparatus Q operates to wind up the code key K⁷. When 75

the winding operation is completed, the relay *j* is deenergized, the motor is stopped, and the relay *G*⁷ is again deenergized. The key *K*⁷ then transmits an indication code to the line wires 4 and 5, which code actuates selector *S*⁷. Current then flows from terminal *B*¹, through contact 13-11-12 of selector *S*⁷, wire 135, and winding 136 of relay *J* to terminal *C*¹. Contact 132-132^b is then closed and current flows from terminal *B*¹, through contact 132-132^b of relay *J*, wire 137, and lamp 138 to terminal *C*¹. The lighting of lamp 138 informs the operator that the signal has returned to its stop position. Similarly, when relay *G*⁵ becomes energized, in response to a westbound train movement past signal *W* the code key *K*⁵ is operated to transmit to the line wires 4 and 5 an indication code which actuates selector *S*⁵. Current from terminal *B*¹ then flows through contact 13-11-12 of selector *S*⁵, wires 139, 143 and 140 and winding of relay *H*⁵ to terminal *C*¹. Relay *H*⁵, therefore becomes energized and is subsequently held in that condition by current which flows from terminal *B*¹, through a manually operable normally closed push button *Z*, wire 141, front contact 142 of relay *H*⁵, wires 143 and 146, and winding of relay *H*⁵ to terminal *C*¹. With this circuit closed, current also flows through the push button *Z* and front contact 142 of relay *H*⁵, wires 143 and 144 to lamp 145 of indicator *X*, lighting lamp 145 to display an indication which persists as long as relay *H*⁵ remains energized, thereby informing the operator that a westbound train has passed the signal *W*, and is occupying the adjacent non-track circuited stretch at the left of the siding. If the despatcher wishes to extinguish the lamp 145 to cancel the indication he may do so by operating the push button *Z*, thereby breaking the stick circuit for relay *H*⁵ and interrupting the circuit for lamp 145 at the front contact 142 thereon. The push button *Z* may then be restored to its original position.

Finally, should relay *G*⁴ be energized due to the passage of an eastbound train past the signal *E*, code key *K*⁴ is operated to transmit an indication code over line wires 4 and 5 which actuates the selector *S*⁴. Relay *H*⁴ is then energized by a circuit similar to the pick-up circuit just traced for relay *H*⁵, and the relay *H*⁴ is subsequently maintained in its energized condition by a stick circuit including the push button *Z* which circuit will be obvious from the drawings. With relay *H*⁴ energized, lamp 146 is lighted and displays a persistent indication to inform the operator that an eastbound train has passed signal *E*, and is occupying the adjacent non-track circuited stretch of track at the right of the siding. The lamp 146 may be extinguished to cancel the indication by operating push button *Z* to break the stick circuit of relay *H*⁴.

It will be apparent that under some conditions of operation, two or more of the starting relays *G* may become energized at one or the same time. If the corresponding code keys were actuated at the same time to supply two or more indication codes to the line wires 4 and 5, the resulting interference between the codes might conflict with the proper operation of the selectors located at the despatcher's office. It will be apparent, however, that the circuit for each of the windings of the clutches *P* includes the back contacts of all of the starting relays *G* to the left of the relay *G* associated with such clutch, so that only one of the clutch mechanisms *P* can be energized at a time. In other words, if two of the starting

relays become energized at the same time, the clutch winding associated with one relay can be energized when both relays are up, while the clutch winding associated with the other starting relay can be energized only when one of the starting relays is in its deenergized position. It follows, therefore, that if two or more of the starting relays *G* become energized at once, the winding of the clutch *P* associated with the relay farthest to the left in Fig. 1 will first be energized to wind up its code key to transmit the corresponding indication code to the line wires in the manner already described. It should be noted that the pick-up circuit for the master relay *j* can be closed only when all of the clutches occupy the positions corresponding to the unwound conditions of the code keys. If one clutch is energized to couple the corresponding code key to the motor shaft, the master relay *j* releases to stop the motor *M* when the key is fully wound. Another clutch can not be energized to couple a second code key with the motor shaft until the first code key has returned to its completely unwound condition. By this arrangement, it will be seen that the code keys are successively wound up and released so that only one of the keys can transmit an indication code to the line wires at a time.

The purpose of relay *f* is to disconnect the relay *N* from the line wire 4 when an indication code is being supplied to the line wires. It will be noted that each of the code keys is so arranged that the lower member of the contact *g* is connected with terminal *C* of the source through the associated brush *g* at all times when the corresponding code key is transmitting a code. This connection is interrupted, however, when all the code keys are at rest. The relay *f* is connected from terminal *B* to a wire 150 which is connected with the lower member of each of the contacts *g*, so that when any one of the keys is transmitting a code, the relay *f* is energized, thereby opening its back contact 24 and disconnecting the relay *N* from the line wires 4 and 5. With this arrangement it is impossible for any of the selectors *S*¹, *S*² or *S*³ to be operated when one of the code keys *K* of the apparatus *Q* is transmitting an indication code to the line wires 4 and 5.

The apparatus is also arranged to prevent the supply of an indication code to the line wires when a control code is being received from the despatcher's office. This lock-out feature is accomplished by means of relay *h* which is supplied with energy over contact 15-16 of selector *S*³, which contact is arranged to be closed when any one of the control codes is being received. Contact 15-16 of selector *S*³ is open when the selector occupies its normal position, but each impulse received by this selector when line relay *N* is operated by a control code moves the movable member 11 of the selector away from its normal position even though contact 11-12 of the selector is closed only in response to the particular code to which the selector is arranged to respond. Any movement of member 11 therefore closes contact 15-16 and energizes relay *h*, and since this relay is slow acting, it remains closed during the reception of any control code. When relay *h* is energized it opens back contact 99 which is included in the circuits for the master relay *j*. With relay *h* energized, it is impossible for the master relay *j* to become energized, and since the circuit for the motor *M* is taken over a front contact of the relay *j*, it follows that it is impossible to wind up any of the keys of the apparatus *Q*.

when a control code is being received from the despatcher's office.

The relay *g* located in the despatcher's office is connected in parallel with the operating windings 10 of the selectors S⁶, S⁷, S⁴ and S⁵, and interposed in series with this relay is an asymmetric unit 152. The unit 152 is so connected as to oppose the flow of current of the polarity supplied to the relay *g* under normal conditions, that is, when relay L is deenergized, so that relay *g* is deenergized under these conditions. When relay L is operating, however, in accordance with an indication code or in accordance with a control code, as a result of operation of any of the code keys K, relay *g* becomes energized each time relay L is energized. Each time relay *g* is energized it completes a circuit from terminal B¹, through wire 153, front contact 154 of relay *g*, wire 155, and the operating mechanism of a single stroke bell 156, to terminal C¹. The bell 156, therefore operates to give an audible indication on each impulse of each code transmitted to the line wires 4 and 5.

The selective and controlling indication apparatus which I have herein shown and described is not limited to use in controlling middle order signals, but may be adapted to the control and/or indication of any apparatus which is located at a distance from the controlling point. For example, the two stick relays F¹ and F³ may be used to control a switch machine SM for operating a track switch, as illustrated in Fig. 6. In this view the contacts 147 and 148 of relays F¹ and F³, respectively, correspond to contacts such as contact 35 which controls signal E in Fig. 1. The apparatus of Fig. 6 is so arranged that the track switch will be operated in one direction when relay F¹ is energized and in the opposite direction when relay F³ is energized, the motor circuit being closed in the first instance over front contact 147 and back contact 148 and opened at contact 149 operated by the switch machine when the switch completes its movement, while in the second instance the motor circuit is closed over front contact 148 and back contact 147 and is opened at contact 151 when the switch completes its movement in the opposite direction.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a movable device, a code key, a relay, means effective upon a change in the position of said device to energize said relay provided said key occupies its normal position, a motor, a clutch controlled by the relay for at times coupling the key with the motor, and means effective when said relay is energized for operating said motor provided said clutch is energized.

65 2. In combination with a movable device capable of at least two operations, a first normally deenergized relay, means for energizing said first relay upon one operation of the device, a second normally deenergized relay, means for energizing said second relay upon a different operation of the device, a motor, two code keys one associated with each said relay and each provided with a code wheel and a spring for driving said wheel, a clutch for each said key arranged to couple the corresponding spring

with the motor to wind up the spring when the corresponding relay is energized, and means controlled by each code key for deenergizing the associated relay when the corresponding spring is wound up. 5

3. In combination with a movable device capable of at least two operations, a first normally deenergized relay, means for energizing said first relay upon one operation of the device, a second normally deenergized relay, means for 10 energizing said second relay upon a different operation of the device, a motor, two code keys one associated with each said relay and each provided with a code wheel and a spring for driving said wheel, a clutch for each said key 15 arranged when actuated to couple the corresponding spring with the motor to wind up the spring, means for actuating each clutch when the corresponding relay is energized, and means for supplying current to the motor when either 20 said relay is energized and for discontinuing such supply when the corresponding spring is fully wound up.

4. In combination with a movable device, two indication relays, a pick-up circuit for one said relay arranged to be closed when said device is moved to one position, a pick-up circuit for the second said relay arranged to be closed when said device is moved to a different position, a motor relay, a motor controlled by the motor 25 relay, two code keys each provided with a code wheel and a spring for driving the wheel, two electric clutches, one for coupling each said spring with the motor to wind up the spring, a pick-up circuit for the motor relay arranged to 30 be closed when either indication relay is energized and all the springs are unwound, a stick circuit for the motor relay for subsequently maintaining such relay closed until one of the 35 springs is completely wound, and a stick circuit 40 for each indication relay controlled by an associated code key and arranged to be opened when the corresponding spring is completely wound.

5. In combination, a movable device, a motor, a code key provided with a code wheel and a 45 spring for driving said wheel, an electric clutch arranged when energized to couple the spring with the motor, means operating upon a change in the position of the device to actuate the motor 50 and to energize the clutch to wind the spring, and means effective when the spring is fully wound to deenergize the motor and the clutch.

6. In combination with a movable device, a motor relay, a motor controlled by the motor 55 relay, a code key having a code wheel and a spring for driving said wheel, a first contact closed only when the spring is unwound, a second and a third contact open only when the spring is wound up, a normally deenergized indication relay having a pick-up circuit closed momentarily at times in accordance with a change in the position of said device, a stick circuit for the indication relay including said second contact, an electric clutch for coupling the spring with the motor to wind the key, a circuit for said clutch including a front contact of the motor relay and a front contact of the indication relay, a pick-up circuit for the motor relay including said first contact and a front contact of the indication relay, and a stick circuit for the motor 60 relay including a front contact of the indication relay and said third contact. 65

7. In combination, a plurality of indication relays, a motor, a plurality of code keys each comprising a code wheel and a spring for driving 70

- said wheel, means effective when any one of the relays is energized to couple the spring of an associated key with the motor to wind the key, and means effective when two or more of such 5 relays are energized at a time to couple the corresponding keys with the motor in a predetermined order and to prevent the operation of each key until the preceding key in such order has completed its operation.
- 10 8. In combination, two sections of railway track, means for supplying track circuit current to the rails of each said section, an interlocking relay having two windings one connected with the rails of each said section, two indication 15 relays selectively controlled by the interlocking relay in accordance with the direction of travel of a train traversing said sections, two code keys controlled by said indication relays, respectively, and selectors controlled selectively by the code 20 keys.
9. In combination, a motor, a plurality of code keys, each comprising a code wheel and a spring for driving such wheel, a magnetic clutch for each code key arranged when energized to couple 25 the corresponding spring with the motor to wind the key, a plurality of normally open contacts, means operating when each such contact is closed to energize a corresponding one of said clutches, and means effective when two or more 30 of said contacts are closed at a time to energize the corresponding clutches in a predetermined order.
10. In combination, a movable device, a relay, a code key comprising a code wheel and a spring 35 for driving said wheel, means for energizing said relay upon a change in the position of said device, means for subsequently holding said relay energized until said key is wound up, a motor, means for energizing said motor when said relay becomes energized, and means for coupling said 40 spring with said motor to wind up the key.
11. In combination, a movable device, a relay, a code key comprising a code wheel and a spring for driving said wheel, means for energizing said 45 relay upon a change in the position of said device, means for subsequently holding said relay energized until said key is wound up, a motor, means for energizing said motor when said relay becomes energized, and means operating when 50 said relay is energized to couple said spring with said motor until the key is entirely wound.
12. In combination, a plurality of indication 55 relays, a plurality of code keys one for each said relay and each comprising a code wheel and a spring for driving said wheel, means for momentarily energizing selected ones of said relays, means for subsequently holding each such relay energized until the associated code key is wound up, a motor relay, means for energizing said motor 60 relay when any indication relay is energized provided said code keys are all unwound, means for subsequently holding said motor relay energized until one of said code keys is wound up, a motor controlled by a front contact of said motor 65 relay, and means effective when any one of said indication relays is energized for coupling the spring of the associated code key with said motor to wind up the key.
13. In combination with a railway track having 70 two adjacent track portions isolated from each other and from the remaining track, a normally closed track circuit associated with each portion, a direction relay for indicating which of said portions were first occupied thus indicating the direction of movement of a train, a train despatch- 75
- er's office, a line circuit connecting said despatcher's office and said two track portions, means including said line circuit for indicating when said direction relay is energized during the passage of a train over one of said two track portions, a signal associated with one of said track portions, and means for controlling said signal over said line circuit.
14. In combination with a railway track having two adjacent track portions isolated from each other and from the remaining track, a normally closed track circuit associated with each portion, a direction relay for indicating which of said portions were first occupied thus indicating the direction of movement of a train, means for indicating at a distant point the simultaneous occupancy of one of said track portions and the energization of said direction relay, a signal associated with one of said track portions, and means for controlling said signal over said line circuit.
15. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for indicating over said line circuit the condition of energization of said track relay and the condition of energization of said stick relay.
16. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for distinctively indicating at said office over said line circuit when said stick relay is energized and said track relay is deenergized and when both said stick relay and said track relay are deenergized.
17. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and indicating means for distinctively indicating at said office and over said line wire the condition of energization of said stick relay for each deenergization of said track relay.
18. In a centralized traffic controlling system, the combination with a section of track of a railway system, a signal associated with said section, a track relay associated with said section, a stick relay associated with said section which stick relay assumes its energized condition when traffic moves in one direction over said section, a local office, a line circuit connecting said office and section, means for controlling said signal over said line circuit, and automatically initiated indicating means for distinctively indicating at said office over said line circuit when said stick relay is energized and said track relay is deenergized and when both said stick relay and said track relay are deenergized.
19. In a centralized traffic controlling system, the combination with a section of track of a rail-

way system, a signal associated with said section, a track relay associated with said section, a stick relay associated with said section which stick relay assumes its energized condition when traffic moves in one direction over said section, a local office, a line circuit connecting said office and section, means for controlling said signal over said line circuit, and indicating means for distinctively indicating at said office and over said line wire the condition of energization of said stick relay for each deenergization of said track relay.

20. In a remote control system comprising a line circuit at times supplied with a control code, a relay, code receiving apparatus, means effective when said relay is in one position to connect said receiving apparatus with said line circuit, a movable device selectively controlled by said receiving means in accordance with said control code, means controlled by said device for at times operating said relay to another position, and means effective when said relay occupies such other position to initiate the transmission of an indication code to said line circuit.

21. In a remote control system comprising a line circuit and code transmitting and receiving apparatuses, a normally deenergized relay, means controlled by a back contact of said relay for connecting said receiving apparatus with said line circuit, means for energizing said relay when a code is to be transmitted, and means controlled by a front contact of said relay for initiating operation of said transmitting apparatus.

22. In a centralized traffic controlling system for railroads comprising an office and a station connected by a line circuit, a plurality of railway traffic governing devices at the station, a series of starting relays, means for selectively energizing said starting relays in response to changes in the condition of said devices or traffic conditions adjacent said devices, a series of sending magnets one for each said starting relay, a circuit for each sending magnet including a front contact of the corresponding starting relay and a back contact of each preceding starting relay in said series, a master relay, means for operating said master relay when any starting relay becomes energized, and transmitting means effective when said master relay is operated to deliver to said line circuit an indication code the character of which depends upon the particular sending magnet then energized.

23. In a centralized traffic controlling system for railroads comprising an office and a station located at spaced points and connected by a line circuit, a plurality of traffic governing devices at one point, a series of starting devices each having normal and reverse positions and each controlled by a particular one of said governing devices, a series of sending magnets one for each said starting device, a circuit for each sending magnet including a reverse contact of the associated starting device and a normal contact of each preceding starting device in said series, a master relay, means for operating said master relay when any starting device is moved to its reverse position, and transmitting means effective when said master relay is operated to deliver to said line circuit a distinctive code the character of which depends upon the particular sending magnet then energized.

24. In a centralized traffic controlling system for railroads comprising an office and a station connected by a line circuit, a plurality of railway traffic governing devices at the station, means controlled from the office for selectively control-

ling said devices, a series of starting relays, means for selectively energizing said starting relays in response to changes in the condition of said devices or traffic conditions adjacent said devices, a series of sending magnets one for each said starting relay, means effective upon the energization of any starting relay for energizing the corresponding sending magnet provided no preceding starting relay is energized and for preventing the energization of any succeeding sending magnet, and transmitting means set into operation when any starting relay is energized provided only the line circuit is clear to deliver to said line circuit an indication code the character of which depends upon the particular sending magnet then energized.

25. In a centralized traffic controlling system for railroads comprising an office and a station connected by a line circuit, a section of railway track at said station provided with a track circuit, a plurality of devices for governing traffic through said section, a series of starting relays, means for momentarily energizing each said starting relay in response to a particular change in the condition of a governing device or said track circuit, a series of sending magnets one for each said starting relay, a circuit for each sending magnet including a front contact of the corresponding starting relay and a back contact of each preceding starting relay in said series, transmitting means operated when any starting relay is energized to initiate the delivery to said line circuit of an indication code the character of which depends upon the particular sending magnet then energized, and means effective when any starting relay is energized to hold such relay in its energized condition until after the initiation of the delivery of the code determined by the corresponding sending magnet.

26. In a centralized traffic controlling system for railroads comprising an office and a station located at spaced points and connected by line wires, a series of starting relays, means for operating said starting relays selectively to store different codes to be transmitted to said line wires, a series of sending magnets one for each said starting relay, means for energizing any said sending magnet when the corresponding starting relay is operated provided no preceding starting relay in said series is operated, a master relay, means for operating said master relay when any starting relay is operated, means effective when said master relay is operated to initiate the transmission to said line wires of a code the character of which depends upon the particular sending magnet then energized and to restore the corresponding starting relay to its original condition, and means at said other point selectively responsive to codes delivered to said line wires.

27. In a remote control system of the code type comprising a line circuit, a quick-acting relay included in said line circuit, a slow acting relay controlled by said quick-acting relay and arranged to be closed for the duration of a code in said line circuit, a series of starting relays, means for operating said starting relays selectively to store different codes to be transmitted to said line circuit, a series of sending magnets one for each starting relay, means for energizing any sending magnet when the associated starting relay is operated provided no preceding starting relay in said series is operated, transmitting means operating when a sending magnet is energized to cause transmission of a distinctive code

to said line circuit provided only said slow acting relay is deenergized, and means effective when said transmitting means becomes effective to restore to its original condition the starting relay 5 which has its sending magnet energized.

28. In a centralized traffic controlling system for railroads comprising an office and a station connected by line wires, two sections of railway track at said station, means for supplying track 10 circuit current to the rails of each said section, an interlocking relay having two windings one connected with the rails of each section, a repeater relay controlled by said interlocking relay, a transmitter controlled by said interlocking relay and by said repeater relay for delivering codes 15 to said line wires, and receiving means at the office selectively responsive to said codes.

29. In a centralized traffic controlling system for railroads comprising an office and a station 20 connected by line wires, a stretch of railway track at the station, means set into operation by the passage of a train through said stretch to transmit over said line wires a distinctive code depending upon the direction of travel of such 25 train, means at said office selectively responsive to such codes for displaying a persistent indication of the direction of travel of the last train through said stretch, and manually operable means at the office for canceling such indication.

30. A system for controlling distant traffic 30 controlling devices of a railway system comprising, two railway signals each when clear giving an indication conflicting with the indication of the other signal when clear, a stick relay for controlling each of said signals, code responsive means for controlling the pick-up circuits for said stick relays, and a stick circuit for each stick relay including a back contact of the other of 35 said stick relays and also including a back contact of a third relay.

31. A system for controlling distant traffic controlling devices of a railway system comprising, two railway signals each when clear giving an indication conflicting with the indication of the other signal when clear, a stick relay for controlling each of said signals, code responsive means for controlling the pick-up circuits for said stick relays, another relay controllable by a code responsive means, and a stick circuit for 50 each stick relay including a back contact of the other stick relay and a back contact of said another relay.

32. A system for controlling distant traffic controlling devices of a railway system by distinctive 55 codes comprising, a track switch, a switch machine for operating said track switch, a stick relay for controlling said switch machine to the normal position, another stick relay for controlling said switch machine to the reverse position, pick-up circuits for said stick relays controlled by code responsive means, another relay, and a stick circuit for each of said stick relays including a back contact of the other stick relay and a back contact of said another relay.

33. A railway train despatching system comprising an office and a distant way station, a pair of stick relays at said station, manually controlled code transmitting apparatus at said office, a pickup circuit for each said stick relay, 65 means responsive to codes from said transmitting apparatus for selectively closing said pick-up circuits, an additional relay at the station controlled by code from said transmitting apparatus, a stick circuit for each stick relay including a back contact of the other stick relay 70

and a back contact of said additional relay, and traffic governing means at said station controlled selectively by said stick relays.

34. A centralized traffic controlling system for railroads comprising; a central office; a distant way station; and means for transmitting distinctive indication impulses from said distant way station to said central office including two stick relays each of which may be picked up by being momentarily energized upon a particular 10 change in traffic conditions, a repeater relay for each of said stick relays, a control circuit for one of said repeater relays including a front contact of its companion stick relay, and a control circuit for the other repeater relay including a 15 front contact of its companion stick relay and a back contact of the other stick relay, whereby said one repeater relay dominates the other repeater relay because it may pick up when both stick relays are up whereas the other repeater 20 relay can only pick up when one of said stick relays is in its deenergized position.

35. A centralized traffic controlling system for railroads comprising; a central office; a distant way station; and means for transmitting distinctive 25 indication impulses from said distant way station to said central office including two stick relays each of which may be picked up by being momentarily energized upon a particular change in traffic conditions, two windings one 30 associated with each stick relay, a control circuit for one of said windings including a front contact of its companion stick relay, and a control circuit for the other said winding including a front contact of its companion stick relay and 35 a back contact of the other stick relay, whereby said one winding dominates the other winding because it may be energized when both stick relays are up whereas the other winding can only be energized when one of said stick relays is 40 in its deenergized position.

36. A centralized traffic controlling system for railroads comprising; a central office; a distant way station; and means for transmitting distinctive 45 impulses from said distant way station to said central office including two starting relays, means controlled by traffic conditions at said station for briefly energizing said starting relays, a stick circuit for each starting relay, a sending magnet for each starting relay, a circuit for 50 one sending magnet including a front contact of the associated starting relay, a circuit for the other sending magnet including a front contact of the associated starting relay and a back contact of the other starting relay, and 55 means effective when either sending magnet is energized to cause said transmitting means to deliver a distinctive code combination.

37. A centralized traffic controlling system for railroads comprising an office and a station connected by line wires, two starting relays at said station, means controlled by traffic conditions at said station for briefly energizing said starting relays, a stick circuit for each starting relay, a sending magnet for each starting relay, a circuit for one sending magnet including a front contact of the associated starting relay, a circuit for the other sending magnet including a front contact of the associated starting relay 60 and a back contact of the other starting relay, a code wheel for each said starting magnet, and means rendered effective by the energization of each sending magnet to cause the associated code wheel to deliver a distinctive impulse combina- 65 70 75

tion to said line wires for the control of indication means at the office.

38. In a dispatching system, an indication relay in the dispatcher's office, controllable from a 5 distant station in accordance with the operated condition of a device to be indicated, an electric lamp having a lighting circuit controlled by said relay, means actuated by the flow of current in said lighting circuit for maintaining said lamp 10 lighted independently of said relay, and manually operable means for rendering said means ineffective and thereby causing the lighting of said lamp to be dependent upon the operated condition of said indication relay.

39. In a centralized traffic controlling system 15 for railroads, an office and a station connected by line wires, a non-track-circuited stretch of track adjacent said station, a section of track at said station having a track circuit, a stick relay at 20 the office effective when energized to indicate the occupancy of said non-track-circuited stretch, means controlled over said line wires and responsive to the occupancy of said station section for picking up said stick relay, and means 25 for releasing the stick relay including a manually operable key.

40. In a centralized traffic controlling system 30 for railroads, an office and a station connected by line wires, a non-track-circuited stretch of track adjacent said station, a section of track at 35 said station having a track circuit, indication means at the office effective when actuated to indicate the occupancy of said non-track circuited stretch; means responsive to the presence and direction of travel of a train occupying said station section for selectively actuating said indication means over said line wires to cause a persistent indication of the occupancy of said non-track-circuited stretch to be displayed, and means 40 for releasing said indication means to cancel said indication.

41. In a centralized traffic controlling system 45 for railroads, means for indicating at a control office the occupancy of a non-track-circuited stretch of track at a remote station comprising indication means at the office effective when actuated to persistently display an indication of the occupancy of said stretch, a track section adjoining said stretch having a track circuit, direction 50 selecting means, means responsive to the occupancy of said section and to said direction selecting means for actuating said indication means, and a manually operable key effective when operated to release said indication means 55 to cancel said indication.

42. In a centralized traffic controlling system

for railroads, means for indicating at a control office the arrival and direction of travel of a train at a remote station comprising two stick relays, each effective when actuated to persistently display an indication of the arrival and 5 direction of travel of a train at said station, a track section having a track circuit at said station, means responsive to the occupancy of said section by a train for actuating one of said stick relays or the other in accordance with the direction 10 of travel of the train, and manually operable means at the office effective when actuated to release said stick relays to cancel said indications.

43. In a centralized traffic controlling system 15 for a single track railroad having a passing siding, a station adjacent the siding and a control office, line wires connecting the office and station, indication means at the office effective when actuated to indicate the presence of a train and its direction of travel in a stretch of single track 20 adjacent to said siding, traffic controlled means at said station selectively responsive to traffic direction, means actuated by the traffic control means at the station when a train passes the station to enter an adjacent single track section 25 to transmit a distinctive code signal over said line wires, and means at the office selectively responsive to said code signal for actuating the corresponding indication means.

44. In a centralized traffic controlling system 30 for railroads, an office and a station connected by line wires, a pair of opposing signals at said station, means responsive to a change in the condition of either signal to transmit one code 35 to said line wires if the signal moves to stop or to transmit a different code to said line wires if the signal moves to clear, indication means at the office selectively responsive to said codes, and means including said line wires for giving at 40 said office an indication of the direction of movement of a train passing said signals.

45. A centralized traffic control system for railroads, comprising an office and a station, means for transmitting from the office to the station a series of current impulses, a pair of opposing signals at the station, a stick relay for each signal, a control circuit for each signal energized only when the corresponding stick relay is energized, means effective when selected impulses are included in said series for energizing a selected one 50 of said stick relays, and a contact opened by each stick relay when energized each said contact being included in the energizing circuit for the other stick relay of the pair.

55

CLARENCE S. SNAVELY.
